APPARATUS FOR WRAPPING CARBON DOLLIES

Armin Kunze, Berlin-Zehlendorf, Germany

Application April 19, 1937, Serial No. 137,839
In Germany April 30, 1936

12 Claims. (Cl. 242—7)

The invention has reference generally to improvements in means for manufacturing carbon dollies and more particularly relates to an apparatus for wrapping carbon dollies.

5 It is the primary aim and object of this invention to provide an apparatus of the above character embodying improved means for effecting an entire automatic winding and wrapping of treated thread directly about a carbon 10 dolly without necessitating the employment of a bag of textile material to hold the carbon in place.

15 More particularly the present invention includes the provision of a wrapping apparatus for carbon dollies in which the thread guide during its reciprocatory movement is moved beyond the front faces of the carbon dolly so as to effect an oblique wrapping or winding of the dolly while at the same time means are provided 20 for effecting two different relative speeds between the carbon dolly and the thread guide, namely, a reciprocatory movement of the thread guide for producing the oblique winding and the slow axial movement of the thread guide for 25 producing the circular winding.

Briefly the invention may be said to reside in the provision of a device for mechanical carbon dollies for galvanic cells including a rotary spindle having a clamping chuck on the lower 30 end thereof for clamping the carbon rod of the dolly with which co-operates an axially slidably mounted thread guide capable of being reciprocated beyond the end surface of the dolly with an operative driving connection between the 35 spindle and the thread guide.

Other objects as well as the nature, characteristic features and scope of the invention will be more readily apparent from the following description taken in connection with the accompanying specification and pointed out in the claims forming a part thereof.

The invention is hereinafter more particularly described with reference to the accompanying drawings which illustrates various 45 devices for carrying out the same.

Figure 1 shows a vertical section through an automatically operating device for wrapping the carbon dollies.

Figure 2 the different operative position of 50 the device according to Figure 1 in plan view,

Figures 3 and 4 part sections through a chucking arrangement of the device shown in Figure 1,

Figure 5 a part section through the feed table 55 of the device shown in Figure 1,

Figure 6 a plan view of the parts shown in Fig. 5,

Figures 7 and 8 an arrangement for applying insulating material for a device according to Figure 1, in front and side elevation.

Figure 9 a similar applying arrangement of a modified form.

Figure 10 a spindle and the parts coating therewith according to Figure 1 to a larger scale,

Figures 11 to 13 different spindle positions, 10

Figure 14 a part section through a clamping and cutting-off arrangement,

Figure 15 a plan view of the arrangement according to Figure 14,

Figures 16 and 17 the arrangement according 15 to Fig. 15 in other positions, and

Figure 18 another device for carrying out the new method.

The wrapping around of the carbon dolly with a thread is carried out according to the invention in such a manner that the thread runs obliquely with respect to the longitudinal axis. Preferably, however, a combined winding is produced in such a manner that the carbon dollies are wrapped round with a thread longitudinally 20 and transversely or obliquely and transversely with respect to the longitudinal axis. The manner of this wrapping will be clearly seen from Figures 10 and 18, in which are also shown two different devices for carrying out the same. According to Figure 10 a carbon dolly 1 is clamped with its carbon rod 2 in a chuck 3 which is fixed at the end of a rotary spindle 4. With the spindle coats a thread guide 5 which is preferably journalled parallel to it and is adapted to 25 be moved to and fro with its arm 6 along the dolly 1, during which it will occupy the two extreme positions shown, of which the lower one is indicated with broken lines 6'.

As will be seen, the thread 7 coming from a 40 bobbin runs through an eye 8 at the end of the arm 6 to the carbon dolly. The oblique position of the thread on the carbon dolly may differ as regards its inclination according to the speed of the to and fro motion of the thread guide. 45

The oblique or longitudinal wrapping of the dolly may also be effected in the manner shown in Fig. 18, through a thread guide 9 circling the dolly in the longitudinal direction. For this purpose the thread guide 9 may for instance be 50 journalled with a ball and socket joint in a fixed guide 11 and be driven by a disc 13 which is rotatable about its axis 12.

The transverse wrapping of the dolly is effected simply by the dolly being moved slowly 55

along past the thread guide in a position of rest or, conversely, by the thread guide being moved slowly along past the rotating spindle.

As the clamping chuck for the carbon rod 2 a self clamping chuck as shown in Figures 3 and 4 is used. This consists of a conical collet 15 which is slit up by slots 14 and the cone of which is indicated at 16. This collet is embraced by an axial sleeve 17 of corresponding conicity, which 10 is rigidly connected by a bolt 18 with a conical pin 19, the end 20 of which extends into the hollow space which serves for the reception of the carbon 2. The carbon is clamped through the downward motion of the spindle 4, the carbon 15 rod forcing the pin 19, 20 upwards and thereby compressing the collet. For opening the collet the sleeve 17 is forced during the upward motion against an abutment, so that it is pushed downwards with respect to the collet. At the same 20 time the cone 19 forces the clamping jaws so far apart that the dolly drops.

It will be readily understood that the new method may be carried out with a device consisting substantially only of a spindle, clamping 25 chuck and thread guide. In order, however, to be able to manufacture the carbon dollies in great quantities, according to the invention an automatically operating device according to Fig. 1 is provided, in which a considerable number of 30 rotary spindles with thread guides are arranged in a circle in a rotary drum-shaped casing which, in the constructional form shown, consists of a cover 21, a drum 22 and a bottom 23. With this drum coats a feed-table 24, into which the dollies 35 can be inserted equidistant from one another by hand by the attendant. The drum and the feed-table are driven by vertical shafts 25 and 26 at a fixed speed ratio to one another. The manner in which the feed-table 24 and the spindles of the drum 22 coat is shown in Fig. 2 diagrammatically. The carbon dollies or their places of support in the feed-table are indicated by 1 and the spindles of the drum 22 by 4.

In order to ensure the carbon rods of the dollies 45 being properly engaged and clamped while the spindles continue to rotate, according to the invention a special arrangement is provided, by which the carbon dollies are guided at the clamping place for a time along the circular path of the spindles. For this purpose, as shown in Figures 1 and 5, the holders 27 for the carbon dollies are arranged in the feed table so as to be radially 50 slideable and resilient and a cam is provided, indicated by 28 in Fig. 2, which compels the holders 55 to travel from the point *a* to the point *b* along a circular path 29, namely the circular path of the spindles 4. In spite of the relatively rapid rotation of the drum 22 there is sufficient time during the movement from *a* to *b* for safely clamping 60 the carbon rods of the dollies.

The details of the holders 27 and of the cam 28 will be gathered from Fig. 5. The carbon 65 dollies are held resiliently in a hard rubber bush 30 which is itself disposed in a soft rubber sleeve 31. For different lengths of dollies an adjusting pin 32 is provided. The holder bears with a roller 33 against the cam 28, on which is suitably provided a centering disc 34 of a centering device to be described below. As shown in Fig. 5, the holder 70 is mounted on two bars 35, 36 which are radially slideable in the feed-table 24 and are forced outwards by a spring 37. As in spite of the cam 28 it is practically impossible so to guide the spindles and the carbon dollies that the axes of the spindles 75 and carbon dollies will exactly coincide, a

special centering device according to Figures 5 and 6 is provided, which consists of a number of slideable members 38 having a forked end 39 and of the already mentioned stationary centering disc 34. It will be seen, that in each case a slideable member 38 engages the corresponding carbon rod 2 and presses it against the rim of the disc 34. This motion is brought about by the radial movement of the holder 27, each slideable member 38 being, as shown in Figure 5, connected with the 10 bar 35 by a pull member 41 which passes over a roller 40. A spring 42 draws the slideable member back into its initial position.

Before the actual wrapping of the dolly commences after it has been clamped in the clamping 15 chuck, according to the invention the bottom 43 of the dolly is covered with an insulating material. This may be effected as shown in Figures 7 and 8 by means of a roller 44 which rotates in a direction B opposite to the direction of travel A 20 of the dolly and dips into a vessel 46 filled with an insulating material 45. The carbon is controlled, as shown, by means of a circular cam 47 and a roller 48 at the top of the spindle 4 in such a manner that the bottom of the dolly brushes 25 past the roller 44.

The wetting of the bottom of the dolly with insulating material, such as paraffin for instance, may also be effected, as shown in Figure 9, by immersing the dolly, the spindle 4 being controlled by means of a cam 49 in such a manner that the dolly moves in the direction of the arrows. The spindle is pressed against the cam by a spring 50.

The aforesaid wetting of the bottom of the 35 dolly with a preferably sticky insulating material has the object of providing the thread, as it is being wound around the relatively smooth dolly, with a hold at the bottom edge of the dolly.

The wrapping of the dolly is effected, as shown 40 in Figures 10 to 13, first of all by the thread-end being held firmly below the dolly and the thread-guide being moved to and fro while the spindle is rotating, so that the oblique winding shown is formed in the manner of the known cross-wound 45 cheeses.

For winding centering ridges the thread-guide is thereupon brought into the position 6' and the dolly with the spindle into the position shown in Figure 11. On the spindle continuing to rotate 50 a centering ridge 51 consisting of superposed threads will then form itself. During this part of the operation the thread 7 is preferably immersed in a vessel fitted with insulating material 52, for instance paraffin. This is effected with 55 a suitably vertically disposed, longitudinally displaceable dipping needle 53, through the eye 54 of which the thread runs.

Whilst the ridge 51 is being wound, the dolly 60 is led past a template 55 which with a suitable opening gives the ridge the desired shape. Immediately following the winding of the upper centering ridge 51 the spindle with the dolly is moved slowly upwards, so that the transverse winding indicated by 56 is formed, which has the 65 special purpose of preventing the diameter of the dolly from changing subsequently. According to Figure 13 the dolly is held in the raised position there shown and at the same time the thread 7 is dipped into the bath 52, so that a 70 paraffin-soaked ridge 57 is formed. For this purpose a template 55 is again used and the thread is finally cut off.

Finally, the dolly is wetted at its bottom end by means of a device according to Figure 7 or 9 75

with insulating material, this external insulating layer being smoothed with a plate 58.

This finishes the dolly and, through the spindle 4 rising and through the clamping sleeve 11 striking against an abutment 59 the clamping chuck is opened, allowing the dolly to fall out.

In Figure 2 these different operations are indicated by defining arrows in the sequence in which they take place. At c the carbon is seized and clamped and the spindle is thereupon moved upwards. The defining arrow d indicates the operation of wetting the dolly bottom with insulating material. Whilst the spindle in question is moving correspondingly to the defining arrow e the dolly is obliquely wound and, immediately following, the winding of the upper centering ridge takes place, as shown by f. The defining arrow g indicates the winding transversely of or around the periphery of the dolly. Thereupon the lower centering ridge is wound, this being indicated by the defining arrow h. Immediately after this the bottom of the dolly is again provided with insulating material (defining arrow i) and finally at the point k the dolly is ejected from the clamping chuck.

For gripping the thread end and at the same time cutting it off a special device as shown in Figures 14 and 15 is provided. This device is fixed to a longitudinally slideable and turnable guide-bar 60 (see also Fig. 1), each spindle having such a gripping and severing device associated with it. The gripping and severing device proper consists, as shown in Figures 14 and 15 of the jaws 61 and 62, a spring 63 pressing the jaw 62 which is fixed to a slideable pin 64 against the stationary jaw 61 which is provided on a guide-sleeve 65 fixed to the shaft 60.

In the advantageous constructional form shown in the drawing only one cutter 66 is provided, 40 which coacts with the edge 67 of the jaw. In order that the thread end shall not slip out of the grippers after the thread has been severed, a thread gripping spring 68 is provided, which is fixed to the jaw 62 and holds the thread against the other jaw before the gripping device is closed and the thread is severed, as illustrated more particularly in Figure 16.

From Figures 16 and 15 it will be seen, that the gripping and severing device is disposed, during the cutting off of the thread next to the dolly between the dolly and the thread-guide 6. In Figure 17 the closed gripping device is shown, holding the thread 7. In this figure is also indicated in broken lines the swung-aside position of the gripping jaws 61 and 62, which before the start of the winding operation are swung into the position in broken lines below the dolly and there hold the thread during the winding of the first convolutions.

As will be seen from Figure 14, the pin 64 is held in the shown opened position of the gripping device by a locking pin 69 which is loaded by a spring 70. For releasing the locking pin 69 a cam is provided which is placed in the path of the pin. The opening of the gripping device is suitably effected by a short cam member which lays itself against a roller 71 provided at the end of the pin 64.

For controlling the longitudinal motion of the spindles, thread-guides, gripping and holding devices and dipping needles, fixed circular cams 47, 72 and 73 are provided as illustrated in Figure 1 (the cam for the dipping needles is not shown). The cams 47, 72, 73 and 74 are secured to a horizontal disc 100 whose boss 101 is secured to the

hollow shaft 102. Since the hollow shaft 102 is rigidly secured to the machine frame the cams 47, 72, 73 and 74 are stationary.

Through the provision of a further ring-shaped cam 74 (see Fig. 1) it is also possible to wrap 5 dollys of a length differing from the normal with the device shown. The cam 74 which controls the spindles with an additional roller 75 is fixed to a circular carrier 76 which is connected by screws 77 with a sleeve 78. This sleeve is provided at its lower end 79 with a thread and is capable of being moved upwards and downwards, by means of a threaded bush 81 which is moved by a toothed wheel 80. The toothed wheel 80 is turned by a hand wheel through a second bevel 10 wheel, (not shown).

In the constructional form shown in the drawing the drive is derived from a shaft 82 which is driven for instance by an electric motor and which through toothed wheels 83 and 84 drives 20 the toothed wheels 85 and 86 and with them the shafts 25, 26.

The spindles 4 which are mounted in the drum, are driven from a driving shaft 82 and by means of the spur wheels 106, 105, the shaft 104 and the 25 spur wheels 103 and 87. The spur wheel 87 is mounted on a rotatably mounted sleeve 88 on which a large spur wheel 89 is mounted. This spur wheel 89 engages in the individual small spur wheels 90 arranged on the periphery or circumference of the spur wheel 89. The spur wheels 90 are axially slideable on the spindles 4 but are each secured against rotation by a groove and key so that all spindles 4 are simultaneously set in rotation during the rotation of the large 35 wheel 89.

For the to and fro motion of the thread guide a crank drive 91, 92 is suitably provided, which is driven from the spindles through bevel wheels 93, 94. With the crank 92 a sliding piece 95 40 is loosely connected and on the thread guide which is pressed by means of a spring 96 against the cam 72 an adjustable collar 97 is fixed by means of which the sliding piece 95 which is moved to and fro takes the thread guide 5 along with it only when the cam 72 has released the thread guide from its lower position of rest.

As will also be seen from Figure 1, bobbins 98 are arranged on the cover 21 of the drum 22, the 50 number of which corresponds to the number of the thread guides and spindles.

With the automatic device shown in Figure 1 a very large output can be produced, so that about one completely wound carbon dolly per second 55 falls out of the device.

The operation of the invention may be reviewed as follows:

The carbon dollys 1 are inserted by hand in the bushes 30 of the continuously rotating feed-table 24 (see Fig. 2 and Fig. 5). As soon as such a carbon dolly, during its circular movement at the point a according to Figure 2 has reached the circle 29 described by the spindles 4 during the rotary movement of the drum 22, the latter 60 will be guided by the cam 28 in such a manner that it is moved between the points a and b on the circle 29 described by the spindles. If the carbon dolly moves further between the points a and b in the feed-table, it is located a certain 65 period directly below the clamping chuck 17 of the spindle 4. During the said period, the spindle 4 is forced downward by the cam 47 so that the clamping chuck engages the carbon rod 2 and during the following upward movement of the 70

75

automatically vertically engaging and releasing dollies, movable thread guides in the drum adjacent each of the spindles and operatively connected thereto, gripping and cutting-off devices 5 arranged adjacent the thread guides, ring shaped cams concentrically arranged in fixed relation adjacent the top of the drum for coacting with the spindles and thread guides to effect vertical movement thereof, a table carried by the upper 10 end of the other vertical shaft and having an edge portion disposed beneath an edge portion of the drum, a plurality of radially disposed and laterally slidably dolly carriers mounted on the table for supporting the dollies in a vertical position and in a circular series about the table so 15 arranged that the dollies will be positioned at

times approximately directly beneath the spindles, a stationary cam on the support for co-operating with the dolly carriers to ensure the proper positioning of each of the carriers with the dolly therein beneath the corresponding spindle, and gearing between the main shafts and vertical shafts for effecting synchronous rotation of the shafts. 5

12. A device as claimed in claim 11, in which a centering disc is arranged on the support below the drum and concentric with the spindle circle, and a centering fork slidably mounted on the rotary table and operatively connected with the adjacent dolly carrier for pressing the dolly at times against the centering disc. 10 15
